UNITED STATES PATENT OFFICE.

CHARLES S. CLIZBE, OF AMSTERDAM, NEW YORK.

MUSIC-RACK AND LEAF-TURNER.

1,037,207.

Specification of Letters Patent. Patented Sept. 3, 1912.

Application filed December 27, 1909. Serial No. 535,030.

To all whom it may concern:

Be it known that I, CHARLES S. CLIZBE, a citizen of the United States, residing at Amsterdam, county of Montgomery, and State of New York, have invented certain new and useful Improvements in Music-Racks and Leaf-Turners, of which the following is a specification.

The invention relates to such improvements and consists of the novel construction and combination of parts hereinafter described and subsequently claimed.

Reference may be had to the accompanying drawings, and the reference characters marked thereon, which form a part of this specification. Similar characters refer to similar parts in the several figures therein.

Figure 1 of the drawings is a view in side elevation of my improved music-rack and leaf-turner showing one of the leaf-turning arms in mid-position. Fig. 2 is a similar view of the lower part of the same on a larger scale, and shown partly in central, vertical section. Fig. 3 is a cross-section of the same taken on the broken line 3—3 in Fig. 2. Fig. 4 is a view in side elevation on an enlarged scale of the rocker-arm for operating the leaf-turning arms. Fig. 5 is a horizontal cross-section of the same taken on the broken line 5—5 in Fig. 4. Fig. 6 is a view on a larger scale than Fig. 1, of the upper portion of the device as seen at an angle of 90 degrees to the plane of the music-rack. Fig. 7 is a cross-section taken on the broken line 7—1 in Fig. 1. Fig. 8 is a view in perspective of the outer end of one of the leaf-turning arms. Fig. 9 is a central vertical section taken through the telescoping rock-shaft whereby the leaf-turning arms are operated.

The principal object of the invention is to conveniently support and turn the leaves of sheet or book-music.

Other objects will appear in connection with the following description.

Referring to the drawings wherein the invention is shown in preferred form, 1, represents a hollow post adapted to be supported in vertical position by means of folding legs, 2, each pivotally connected at its upper end with a sleeve, 3, adapted to slide upon the post, 1, and having a tapered screw-threaded portion adapted to receive the thumb-nut, 4, whereby said sleeve may be clamped in adjusted position upon the post 1. Each of said legs, 2, is connected

with the lower end of the post, 1, by means of a link, 5, pivoted at one end to the lower end of the post, and at its other end to an intermediate part of the leg 2.

The post, 1, is preferably made up of telescopic sections, as shown in Fig. 1, the upper of said sections being designated, 1^a, and adapted to slide within the lower main section, which lower main section, 1, has a tapered screw-threaded split upper end, 6, adapted to be clamped upon the section, 1^a, by means of a thumb-nut, 7, fitting said tapered screw-threaded portion. By loosening the nut, 7, the sections, 1 and 1^a, can be drawn apart or forced together to vary the length of the post formed thereby, and can be locked by the nut, 7, in the selected position. Upon the upper end of said vertical post is fixed an offsetting-head, 9, upon which is pivotally mounted at, 10, a music-rack, 11, adapted to support book-music or sheet-music opened or spread out to the view of a musician using the device. The rack thus pivotally mounted is adapted to be supported at the proper angle for use by means of a spring-latch, 12, carried by the main-frame member of the rack and adapted to enter a suitable aperture in the stud, 13, fixed upon a bracket, 14, rigidly mounted upon the head 9. When, by manipulation of the latch, 12, the rack is released from the stud, 13, the rack can be swung back to a position substantially parallel with the post, 1, as indicated by dotted lines in Fig. 1.

As shown in Fig. 6, the rack is made up of pantographic members adapted to be folded to the position indicated by dotted lines, or expanded to the position shown by solid lines, in the usual manner.

I pivotally mount upon the stud, 13, one or more leaf-turning arms, 15, each having means for embracing a leaf of sheet or book-music.

As shown in Figs. 6 and 8, the arm, 15, is formed with a channel, 16, adapted to receive the bottom edge of the leaf, and with a pair of wire-fingers, 17, adapted to embrace between them the upper portion of the leaf. As shown, the arms, 15, swing on an axis which is parallel with the plane of the rack, 11, and oblique to the axis of the post 1. Any desired number of leaf-turning arms, 15, may be thus rotatively mounted upon the stud, 13, the hubs of said arms being loosely confined on said stud by

the spring-latch, 12, when the rack is in position for use.

As a preferred means for swinging each leaf-turning arm, 15, to turn a leaf and carry the same from the righthand side to the lefthand side of the rack, I have shown the several leaf-turning arms formed with a downwardly-projecting finger, 19, adapted in certain positions to be engaged by a yielding latch, 20, mounted upon a rocker-arm, 21, fixed upon the upper end of a rock-shaft, 22, which is rotatively mounted in the hollow post formed by the sections 1 and 2.

As shown in Figs. 6 and 7, the rock-shaft, 22, is located slightly to the right of a vertical plane passing from front to rear through the stud, 13, so that the arc traversed by the yielding latch, 20, when the shaft, 22, is rocked is eccentric to the path 20 traversed by the downwardly-projecting finger, 19, on a leaf-turning arm. The eccentric relation thus established between the leaf-turning arm and the latch, 20, is such that the latch, 20, is adapted to engage, 25 yieldingly pass, and interlock with, a depending finger, 19, of a leaf-turning arm when the shaft, 22, is rocked to the right, as seen in Figs. 6 and 7, and to pass out of engagement with said finger, 19, and release the 30 same just before the finger, 19, reaches the limit of its swinging movement to the left, gravity and the inertia of the moving leaf-turning arm being sufficient to complete its swinging movement, thus making it possible 35 for the latch, 20, to be returned to position to engage and interlock with the next leaf-turning arm to be operated, without in its return movement engaging any of the leaf-turning arms which occupy a position at the 40 lefthand side of the rack.

As a means for operating the rock-shaft, 22, from time to time in the various relative positions of the post-sections, 1 and 1^a, I have shown said rock-shaft flattened on one 45 side, as at, 23, and adapted to fit within a tubular shaft-extension, 22^a, having its upper end flattened on one side at, 23^a, whereby a telescopic movement of the parts, 22 and 23, is permitted, while said parts are 50 locked together with regard to rotative movement. The lower end of the shaft-section, 22^a, is fixed to a shaft-section, 22^b, provided with a spiral-groove, 24, adapted to receive a pin, 25, fixed upon a sliding sleeve, 26, and adapted to play in a vertically elongated slot, 27, formed in the post-section, 1, as shown in Fig. 2. The sleeve, 26, is yieldingly supported by a coil-spring, 28, and has 55 projecting from its lower end a foot-rest, 29, whereby the sleeve can be depressed against the force of the spring 28.

The rocker-arm, 21, normally occupies a position at the limit of its rocking movement to the left, as indicated by dotted lines 60 in Figs. 6 and 7, and in using the leaf-turn-

ing apparatus the book or sheet-music is placed upon the rack with a leaf to be turned extending toward the right and inserted in one of the leaf-turning arms, which occupies the position shown by solid lines in Fig. 6. 70

The user of the device, when it is desired to turn said leaf, simply presses downward with his foot upon the foot-rest, 29, thereby forcing the sleeve, 26, and pin, 25, downward, the downward passage of the pin, 25, 75 along the spiral groove, 24, serving to partly rotate the shaft-sections, 22^b, 22^a, and 22, and thereby cause a rotative movement from left to right of the rocker-arm, 21, causing its latch, 20, to engage the finger, 19, on said 80 leaf-turning arm, or, if there be more than one of said leaf-turning arms, to engage the uppermost thereof. As soon as the user removes his foot from the foot-rest, 29, the spring, 28, automatically forces upward the 85 sleeve, 26, and pin, 25, causing a reverse movement of the rocker-arm, 21, which serves to carry the engaged leaf-turning arm from the right to the left. Thus by successive applications of the foot of the user 90 to the foot-rest, 29, the successive leaf-turning arms, if a plurality be employed, can be operated at the will of the user.

The yielding latch, 20, may be of any known form, a preferred form thereof being 95 shown in Figs. 4 and 5, wherein the latch is formed by a slide-bolt, 30, movably mounted in a chambered slideway in the rocker-arm in engagement with a coil-spring, 31, and having its movement limited by a screw, 32, 100 inserted through the wall of said slideway, and occupying a slot or groove in the side of said bolt.

I have shown the rack provided on its opposite ends with rotatively mounted off-set wire-fingers, 34, adapted to overhang and hold down the surplus leaf or leaves when the book or sheet-music consists of more leaves than are to be automatically turned by the apparatus. The wire-fingers, 105 34, are pivotally mounted upon the outer ends of arms, 35, projecting beyond the side-members of the rack, and are thereby given capacity for use with book or sheet-music of 110 greatly different sizes. By having these 115 fingers offset as shown at, 36, the fingers are adapted to engage by their extreme swinging ends the leave or leaves to be held down upon the rack although the same may be of considerable thickness, and to clamp said 120 leaves between said finger and said rack. This feature of my invention adapts the 125 rack for supporting book or sheet-music for use, whether or not the leaves are to be turned by the foot-operated apparatus.

The wire fingers, 17, which are adapted to embrace between them a leaf to be turned, are pivotally mounted at their lower ends at, 37, upon the leaf-turning arm which is 130 formed with a bead or flange, 38, along its

upper edge on each side, which bead or edge is provided with notches, 39, adapted to receive the respective wire-fingers, 17, in different positions of rotative adjustment, whereby they are adapted to occupy either the position shown in solid lines, or either of the positions indicated by dotted lines in Fig. 6, to adapt the arm to properly support and turn leaves of different sizes. The 10 resilient nature of the wire-fingers, 17, permits them to be sprung out of one notch, 39, and into another when desired.

For storing or transporting the device, the legs, 2, can be folded substantially parallel 15 with the post, 1; and the rack, 11, can be folded and swung back substantially parallel with said post, and the leaf-turning arms can be removed from the stud, 13, permitting the apparatus to be packed in a comparatively small space.

For convenience in returning one or more of the leaf-turning arms into position to be operated by the leaf-turning mechanism above described, I have shown the channeled members of the leaf-turning arms of different heights near their ends, so that when a plurality of the arms are resting upon the lefthand side of the rack, each upper arm presents near its end a greater downward 25 projection as at, 40, than the next lower or adjacent arm, the leaf-turning arms thus having lower edge-portions of successively greater downward projection in the order in which said arms are operated by said mechanism. The user of the device can thus quickly turn from left to right the uppermost arm by engaging with his finger the downwardly-projecting end-portion, 40, thereof. If, however, he wishes to return 30 all of the arms he can readily do so by engaging with his finger the lowermost arm at a point somewhat nearer the axis of rotation, at which point all of the arms are of substantially the same height.

45 What I claim as new and desire to secure by Letters Patent is—

1. In a device of the class described, and in combination, a post, means for supporting the post in upright position, a tubular slide movably mounted upon the lower end of said post, a foot rest fixed on said slide, resilient means surrounding said post between the slide and in contact therewith for normally holding said slide in raised position, a rock shaft mounted within said post and having a spiral groove at its lower end, a projection on said slide engaging said spiral groove to rotate said rock shaft, a bracket secured upon the upper end of the 50 post, a leaf-turning arm rotatively mounted upon said bracket, and means on said rock shaft adapted to engage with and operate said leaf-turning arm.

2. In a device of the class described, and 55 in combination, a post, means for supporting

said post in upright position, a vertically movable tubular slide mounted upon the lower end of said post, said slide being enlarged at its lower end to provide a socket, an abutment at the juncture of said socket 70 with said slide, a foot-rest fixed on said slide, resilient means surrounding said post, and projecting into said socket and engaging said abutment whereby to movably hold said slide in a normally raised position, a rock shaft mounted within said post, a spiral-groove -and -pin -connection between said rock shaft and said slide for rotating said rock shaft when the slide is moved, a supporting rack mounted upon the upper 85 end of said post, a leaf-turning arm rotatively mounted on said rack eccentrically to said rock shaft, a rocker arm on the upper end of said rock shaft, and a latch device carried by said rocker arm automatically 90 engageable with said leaf-turning arm and remaining in engagement therewith during a part only of its movement, said latch device adapted to be released from said leaf-turning arm by reason of the eccentricity 95 of their respective paths.

3. In a device of the class described, and in combination, a post, a rack pivotally mounted upon said post, a stud mounted upon said rack and movable with it, a leaf-turning arm removably pivoted upon said stud, a latch carried by said rack, adapted to engage the outer end of said stud when the rack is in position for use, and operative means carried by said post for moving said 100 leaf-turning arm when the rack is in said position for use.

4. In a device of the class described, and in combination, a post, a rack pivotally mounted upon said post, a stud mounted 105 upon said rack and movable with it, a leaf-turning arm removably pivoted upon said stud, a latch carried by said rack adapted to engage the outer end of said stud when the rack is in position for use, foot-operated 110 mechanism mounted on the lower end of said post, and operating connections between said foot-operated mechanism and said leaf-turning arm for rotatively operating said arm when the rack is in said position for 115 use.

5. In a device of the class described, and in combination, a post, a book-supporting rack pivotally mounted on said post; a removable leaf-turning arm pivoted on said 120 rack, a rock shaft mounted within said post, a slide surrounding said post, means carried by said slide for operating said rock shaft, engaging means on the upper end of said rock shaft operating said leaf-turning 125 arm, and a leaf-engaging finger pivotally mounted upon each side of said rack to cooperate with the same and clamp therebetween the leaves of a book below those to be engaged by the leaf-turning mechanism. 130

6. In a device of the class described, and in combination, a post comprising a pair of telescoping tubular members, a rock shaft mounted within said post and comprising a pair of cylindrical members, the adjacent ends of said members being formed with correspondingly located flattened portions, whereby said sections are locked together with regard to rotative movement while free to slide one upon the other, a spiral groove being formed in the lower end of said rock shaft, foot-operated means for rocking said rock shaft through the medium of said groove, a leaf-turning arm, and means on the outer end of said rock-shaft for engaging with and turning said arm.
7. In a device of the class described, and in combination, a telescoping post, a telescoping rock shaft mounted within said post comprising a cylindrical member flattened along one side from end to end and a cylindrical tube adapted to receive said flattened

member and having a correspondingly flattened side for a short distance only adjacent to one end, leaf-turning members actuated by said rock shaft, and a slide on the lower end of said post and means carried by said slide for operating said rock shaft.

8. In a device of the class described, and in combination, a pivotally mounted leaf-turning arm channeled to receive the bottom edge of a leaf and having outturned flanges along its upper edges provided with registering series of notches, and a pair of yielding fingers pivoted to the arm against its opposite sides and adapted to be swung into any one of the notches in said flanges.

In testimony whereof, I have hereunto set my hand this 18th day of December, 1909.

CHARLES S. CLIZBE.
